CUSHION ARCH SUPPORT

Charles Saladino, Middle Village, Long
Island, N. Y.

Application February 12, 1934, Serial No. 710,770

1 Claim. (Cl. 12—142)

This invention relates to new and useful improvements in a shoe and has more particular reference to a shoe provided with an arch pad.

The invention has for an object the construction of a shoe with an arch pad, in which the arch pad is arranged in a novel manner within the shoe.

Still further the invention particularly proposes the adjustment of the arch pad upon the inner face of the shoe upper in a manner so that the shoe may be constructed thereafter in a conventional manner.

As another object of this invention an arrangement is proposed for encasing and covering said pad within the shoe upper.

Furthermore as another object of this invention it is proposed to teach a method whereby the shoe may be lasted with the pad so as to be a perfect fit upon the foot.

More particularly an arrangement is proposed whereby a tab projects from said pad and is adapted to be tacked down upon the last during a certain portion of the manufacture of the shoe and thereafter cut off so that the shoe is properly lasted even though it contains the arch pad.

Furthermore as another object of this invention an arrangement is proposed whereby the arch pad is reinforced with flexible stiff strips.

Furthermore the invention also proposes an arrangement whereby said flexible stiff strips may be removed from the inner side of the shoe when desired.

As another object of this invention it is proposed to construct an article as mentioned which is simple and durable and which may be manufactured and sold at a reasonable cost.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure:

Fig. 1 is a side elevational view of a part of a shoe shown upon a last and including the arch pad according to this invention.

Fig. 2 is a bottom plan view of Fig. 1.

Fig. 3 is a sectional view taken on the line 3—3 of Fig. 2.

Fig. 4 is a fragmentary inside elevational view of a portion of the shoe upper showing the vicinity provided with the pad.

Fig. 5 is a sectional view taken on the line 5—5 of Fig. 4.

Fig. 6 is a fragmentary sectional view taken on the line 6—6 of Fig. 4.

Fig. 7 is a fragmentary longitudinal sectional view of the shoe, illustrating in detail the inner lining thereof and an arch pad according to a modification of this invention.

Fig. 8 is a horizontal sectional view taken on the line 8—8 of Fig. 7.

Reference numeral 10 indicates a last of conventional construction upon which a partially finished shoe is illustrated so that the invention may be better understood. This part shoe comprises a shoe upper 11 having a lining 12 and connected with an insole 13 and a welt 14. At the inner longitudinal arch of the last 10, the shoe upper is provided with a pad 15. This pad is attached upon the inner face of the shoe upper 11. More particularly the pad 15 comprises a felt or other similar pad and is secured in place upon the inner surface of the shoe upper by a covering element 16 engaging over the pad and stitches 17 securing the covering element together with the shoe upper. The pad 15 is shown provided with a tab 18 projecting from its lower end. The pad has a straight edge for extending along the welt of the shoe and a curved upper edge so as to properly fit the inner longitudinal arch of the foot.

The tab 18 is used solely during the manufacture of the shoe and before the shoe is completed this tab is cut off. The function of the tab may best be understood by examining Fig. 2. In this figure the shoe upper is ready to be sewed to the insole 13. The insole is provided with a conventional cut 19 extended along the bottom side for the inseam stitches. The welt 14 is placed along the outside of the bottom edge of the shoe and the shoe upper held properly against the last by tacking the tab 18 down. In Fig. 2 the dot and dash lines 18 indicate the tab and the small circles 18' indicate the tacks for holding the tab down. Then the shoe upper may be sewed to the insole and welt in the conventional fashion except in the area where the tab 18 is located. When the sewing reaches this area it is necessary that the tab be first cut off and then the sewing continued.

The shoe is completed in a regular fashion with the necessary soles and heels and the other trimmings such as bows, etc. Of course the shoe must have all other improvements necessary in shoe constructions as for example, the stiffening members for the toe portion and the heel portion of

the shoe upper. These parts are constructed in the conventional manner either by stiffening elements being placed between the shoe upper and the lining or suitable cemented material adapted 5 to be thereafter hardened to produce the necessary stiffness.

In Figs. 7 and 8 another embodiment of the invention has been disclosed in which reinforcement strips are used in conjunction with the arch 10 pad 15. More particularly several reinforcement strips 20 extend through the pad 15 and have their inner ends 21 engaging against the sewing which secures the pad upon the inner face of the shoe upper. The other ends of the strips 20 project 15 from the covering material 16 of the pad and engage into small pocket elements 21 attached upon the inner face of the shoe upper. The lining 12 of the shoe upper is formed with several openings 22, preferably these openings may be in the 20 form of button holes, arranged in the vicinity of the pocket elements 21. The strips 20 are provided with small openings 23 aligned with the openings 22 in such a manner that implements may be engaged into the openings for the purpose 25 of ripping the reinforcement strips and opening the ends in such a manner as to disengage the ends through the opening 22. This permits the removal of the reinforcement strips when desired.

It will be found that the reinforcement strips 30 are of exceptional advantage in serving to hold the arch of the foot through resting periods to relieve any strain upon the foot. When it is ad-

visable that the strips 20 be withdrawn from the shoe, this is easily accomplished through the openings 22 as previously described.

It is to be understood that my arch pad may be used in any size, design, and type of shoe regardless of whether it is a turn shoe, McKay, welt or pasted shoe.

While I have shown and described the preferred embodiment of my invention, it is to be understood that I do not limit myself to the precise construction herein disclosed and the right is reserved to all changes and modifications coming within the scope of the invention as defined in the appended claim.

Having thus described my invention, what I 15 claim as new and desire to secure by United States Letters Patent is:

A process for manufacturing a shoe with an arch pad consisting in securing a pad upon the inner face of a shoe upper in the inner longitudinal arch region, securing the portion of the shoe upper provided with the pad tightly against a last by temporarily fastening a tab forming a part of said pad to the bottom of the last, placing an insole upon the bottom of the last, lasting the 20 upper and lining over the insole, and inseaming the insole, the lower edge of the shoe upper and lining and the welt for the shoe, said tab being cut off and removed before the portion of the shoe adjacent thereto is inseamed.

CHARLES SALADINO.
